UNITED STATES PATENT OFFICE

2,439,182

BLOWER CONTROL DEVICE FOR SUCTION
CLEANERS

Joseph H. Nuffer, Toledo, Ohio, and Lynn H. Latta, Deerfield, Ill., assignors to Air-Way Electric Appliance Corporation, Toledo, Ohio, a corporation of Delaware

Application September 27, 1943, Serial No. 503,918

1 Claim. (Cl. 230—47)

1

This invention relates to suction cleaners of the type in which the filtering and suction units are both enclosed within a rigid housing to which a dust-laden air stream is led through a flexible suction hose from a cleaning tool.

An object of the invention is to provide a vacuum cleaner which has provision for a blower connection direct to the base of the cleaner, and wherein such blower connection need not pass through the cover.

Another object is to provide a novel and improved arrangement for normally closing the blower outlet and at the same time opening an outlet or plurality of outlets for normal discharge of the air downwardly through the base of the cleaner so as to avoid undesirable effects of a horizontally projected discharge stream.

These and other objects of the invention will become apparent from a perusal of the following specification taken in connection with the accompanying drawings, in which:

Fig. 1 is a longitudinal vertical sectional view of a suction cleaner embodying the invention;

Fig. 2 is a horizontal sectional view of the same taken as indicated by the line 2—2 of Fig. 1, and

Fig. 3 is a rear elevation of the lower portion of the cleaner.

As an example of one form in which the invention may be embodied, we have shown in the drawings a suction cleaner wherein the suction unit, indicated generally at 10, and the dust collecting and air filtering unit, indicated generally at 12, are mounted in side by side relationship upon a low base 14 with the axis of both units vertical or substantially vertical, wherein a cover 16 is adapted to form, together with the base 14, a housing enclosing a chamber 17 in which the suction and filtering units 10 and 12 are accommodated.

While the axis of the filtering unit 12 may not be exactly vertical, it is preferred to have it arranged on a generally vertical axis, in order that the dust laden air stream may enter the filtering and collecting receptacle 20 at the upper end thereof, thus leaving the entrance portion of the receptacle always clear until the receptacle is substantially full of collected dust and refuse.

The cover 16 is roughly "tear drop" shaped, the wall thereof being extended downwardly around the suction and filtering units 10 and 12, to the plane of the base 14. The rear end of the cover 16 is hinged as on 18 to an arch shaped upward extension 22 of the rear end of the base 14. A latch 26 normally latches the lower forward portion of the cover 16 to the base 14. By releasing

2

the latch 26, the cover 16 may be lifted to a position wherein its lower edge lies in a substantially perpendicular plane, substantially completely exposing the suction and filtering units 10 and 12 for servicing operations. For example, with the cover thus raised, the carbon brushes 30 of the suction unit 10 may be readily removed and replaced, and a filled receptacle 20 may be removed and replaced by a fresh receptacle.

10 The filtering unit 12 includes the receptacle 20, a perforated supporting liner 36 encircling the receptacle 20, and a tubular casing 38 encircling and spaced from the liner 36. At the upper end of the casing 38 is an annular channel 40 in which 15 is mounted a gasket 42 of compressible material such as for example, soft rubber, and the receptacle 20, which is preferably of porous paper so that it may be disposed of when filled, is provided at its upper end with a non-porous flange 44 resting upon the gasket 42.

The cover 16 is formed with an annular clamping flange 46 adapted to clamp the flange 44 against the packing ring 42, and with a delivery nozzle 48 receivable in a central opening 50 in a 25 non-porous top member 52 which is secured to the receptacle 20. The top member 52 may be connected integrally with the flange 44 by an offset portion 54 by means of which the top member is stitched to the receptacle 20. The nozzle 48 30 carries a sealing ring 56 of compressible material, such as soft rubber, which is adapted to seal the nozzle to the top 52. The parts are so arranged that the sealing of the nozzle 48 to the top 52 and the clamping of the flange 44 against the packing 35 ring 42 is effected by moving the cover 16 to closed position and latching it in that position.

Formed in the cover 16 is an inlet 58 which is connected to the nozzle 48 by a short duct 60. To the inlet 58 may be attached one end of a 40 conventional flexible suction hose to the other end of which is connected the usual cleaning tool. It is contemplated that the body of the cleaner, shown herein, may be pulled about by the hose thus attached to the inlet 58.

45 The casing 38 of the filtering unit 12 is mounted at its lower end upon a pair of arcuate seats 69 and 70 formed integrally with and projecting upwardly from the base 14. Spaces 68 between the seats 69 and 70 permit air to flow from the lower 50 end of the filtering unit to the upper end of the suction unit as indicated by the arrows. An in-turned flange 71, on the lower end of the casing 38, provides the means for attaching the casing 38 to the seats 69 and 70 in connection with suitable attaching elements such as the screws 73

extended upwardly through the base 14 and the seats 69 and 70 and threaded into the flange 71.

The suction unit 10 includes a conventional motor casing 78 having air inlet openings 76 at its upper end and mounted at its lower end upon a fan casing 84 which has air outlets 85 in its bottom wall. The fan casing 84, which is preferably formed of a pair of stampings joined together by flange means 80, extends into a well 81 defined within an annular flange 79 extending upwardly from the base 14. The fan casing 84 is mounted upon the flange 79 through the medium of an annular plate 77 secured by screws 82 to the flange 79, and a vibration absorbing ring 83 of soft rubber or the like bonded to the ring 77 and to a ring 75 which is secured to the flange 80 of the fan casing.

The rear portion of the flange 79 merges with the extension 22, and the well 81 communicates with a blower outlet 87 formed in the extension 22. A valve disc 88, secured to a trunnion 89 pivoted in the base 14 centrally of the well 81, has an annular series of apertures 90 adapted to normally register with discharge openings 91 in the base 14. The disc 88 is also provided with an upwardly extending valve element 92 which is adapted, when the openings 90 and 91 are in register, to close the blower outlet 87. A lever 93, secured to the trunnion 89, is provided with a latch element 95 adapted to enter one opening in the base 14 to determine the above described position of the valve disc and to be withdrawn from that opening, utilized as a means to swing the lever 93 for rotating the valve disc 88, and to enter a second opening (indicated at 96 in dotted lines in Fig. 2), for determining a position of the valve disc 88 wherein the normal discharge openings 91 are covered by imperforate portions of the valve disc 88 and the valve element 92 is moved away from the blower outlet 87. In this second position of the valve disc, the normal discharge openings 91 being closed and the blower outlet 87 being opened, the discharge from the suction unit 10 will be concentrated in the blower outlet 87, so that the discharge may be utilized for operating blowing tools at one end of a hose the other end of which is adapted to be attached to the blower outlet 87.

The cover 16 is sealed to the base 14 by means of a gasket 97 mounted in a channel 98 which extends around the periphery of the base 14 and over the extension 22, and a flange 99 projecting inwardly from the wall of the cover 16 and adapted to engage the gasket 97.

The base 14 is mounted upon three casters 100, arranged with a forward caster on the central longitudinal axis of the base and two rearward casters spaced laterally on either side of said longitudinal axis.

The resilient motor mountings 86, 83, 75 seal 60

the well 81 from the chamber 17 so that the latter may function to transmit suction from the upper end of the suction unit 10 to the lower end of the filter unit 12. The gasket 87, sealing the cover 16 to the base 14, makes it possible for the pressure in the chamber 17 to be lowered so as to thus transmit suction from the suction unit to the filter unit.

In applicants' copending Patent 2,388,279, the following subject matter disclosed but not claimed herein is claimed: a suction cleaner having a base on which are mounted suction and filtering units and a cover enclosing such units, the cover being provided with means forming a portion of the air inlet duct communicating with the filtering unit.

We claim as our invention:

In a suction cleaner, a base, a suction unit on said base having an air inlet and an air outlet, an arch shaped upward extension on said base at one end thereof, said extension providing a blower outlet open at the outer end and communicating with the suction unit outlet at its inner end, a cover on said base enclosing said suction unit, said base being apertured in the region of said upward extension and at a point communicating with the suction unit outlet to enable normal discharge of air from the suction unit, a pivotally mounted valve disc on said base having apertures adapted to register with the apertures in the base, an upwardly extending valve flange on the periphery of the disc adapted when the disc and base apertures are in registry to close the blower outlet, and means for turning the valve disc, said last means being accessible from the underside of the base.
